ORGAN

Maurice E. Hardy, Pelham, N. Y., assignor to
Aeolian-Skinner Organ Company, Inc., Dor-
chester, Mass., a corporation of Massachusetts

Application February 15, 1935, Serial No. 6,704

8 Claims. (Cl. 84—346)

This invention relates to an improvement in organs and more particularly in the shutter mechanism thereof.

Heretofore it has been the practice to arrange the shutters so that when closed they are in a common plane and when fully opened they assume an angle of substantially 45°. It has been found that these shutters, not only while being opened, but even when fully opened, cause considerable deflection of the sound waves, and that the high frequency waves of a tone as a result of this deflection are completely lost. The result is an unbalanced mixture which can not give the even, uniform tone desired by the organist.

The primary object of this invention is to provide swell shutter mechanism in which the shutters, when fully opened, assume a position at an angle of approximately 90° to the mechanism frame to provide passages leading from the sound compartment into the chancel or auditorium.

A further object of this invention is to provide swell shutter mechanism in which the shutters, when closed, assume a position at an angle of approximately 45° to the mechanism frame.

Another object of this invention is to provide swell shutter mechanism comprising a plurality of shutters pivotally mounted midway their width and means for rotating alternate shutters in opposite directions for opening or closing passages therebetween, the parts of each adjacent pair of shutters at one side of the pivot points moving toward each other and the parts at the other side moving away from each other.

These and other objects will appear from an examination of the following description and of the drawing which forms a part thereof, and in which

Fig. 1 is a view in elevation of a shutter mechanism embodying this invention;

Fig. 2 is a sectional view thereof taken along the line 2—2 on Fig. 1, the shutters being shown in full lines in the closed position and in dotted lines in the fully opened position; and

Fig. 3 is an enlarged view of a detail of the shutter mechanism.

The shutter mechanism 10 selected for the purpose of illustrating this invention comprises a frame 11 in which a plurality of shutters 12 are pivotally mounted. These shutters, when closed, prevent the escape of sound waves from a sound compartment to a chancel, auditorium or other room, the direction of travel, when the shutters are opened, being indicated, for the purpose of the following description, by the arrows 35 placed on Fig. 2.

When the mechanism is closed, the shutters assume a position at 45° to the plane of the frame, and when opened they assume a posi-

at 90° thereto. This is clearly shown in Fig. 2. The relative relation of the shutters, when the mechanism is closed, is shown in Fig. 3, the edge of one shutter 12 abutting one side of the edge of an adjacent shutter 12. At the inner ends of the frame are mounted shelves 13 and 14 against which, when the mechanism is closed, edges of the shutters at each end bear, the edge of the left shutter abutting the side of the shelf 13 and the edge of the right shutter abutting the edge of the shelf 14. The side edges of the shutters and shelf against which the edges of the shelf and shutters bear are recessed to receive pads 15 of felt or similar material to seal the closures and eliminate clattering when the shutters are closed. Suitable checks (not shown) may be provided to stop the movement of the shutters.

The shutters are pivotally mounted at approximately the center axes upon pins 16 which enter the walls of the frame 11. Mounted upon each shutter is an arm 17, the arms of alternate shutters extending in opposite directions from the frame. The ends of the arms 17 support and are pivotally pinned to trace rods 18 which extend at opposite sides of the shutters. The reciprocation of the rods obviously causes the opening and closing of the shutters.

Various means may be provided to reciprocate the rods 18 as, for example, the following means which I have elected to show in the drawing. Mounted upon the upper side of each rod 18 near one end (the right as shown in the drawing) is a block 20 to which is pivotally secured one end of a link 21. The link 21 is similarly secured at the other end to an arm 22 fixed upon a rock shaft 23. The shaft 23 is oscillated by a balanced pedal 24 connected by a link 25 to an arm 26 mounted upon a rock shaft 27. A link 28 connected at one end to a second arm 29 on the shaft 27 and at the other end to an arm 30 fixed upon the shaft 23 transmits the motion of the pedal to the rock shaft 23. In accordance with the usual practice the pedal 24 is depressed by the organist's toe to open the shutters, and closed by pressure being applied to the pedal by the organist's heel. Suitable means (not shown) limit the opening movement of the shutters so that they do not pass beyond the fully open 90° position shown in dotted lines in Fig. 2.

When the mechanism is closed, the adjacent shutters are at right angles to each other and when it is opened, the shutters are parallel. This is clearly shown in Fig. 3 by full and dotted lines. When the shutters are opened, the edges of each pair of adjacent shutters which are in contact when the shutters are closed move away from each other and thus the width of the passage is uniformly increased by both shutters; the opposite edges meantime are moved

toward each other and similarly act uniformly to decrease the width of the passage. The 90° position assumed by the fully opened shutters provides a plurality of passages from the sound compartment through which the sound waves pass freely without any deflection, flowing around the edges of the shutters in a manner similar to the flowing of water around the buttresses of a bridge. Thus the tone is without distortion and includes waves of both high and low frequencies.

The shutters may of course be operated by any one of the various types of electropneumatic swell engine or two swell engines may be employed to operate the two series of shutters. In these cases the swell pedal would operate a series of contacts connected to the magnets of the swell engine or engines. The shutters may be moved alternately through the series of stations, thus obviating any possibility of jamming when closed, or may be opened individually in series by "individual shutter action".

The structure herein shown and described exemplifies one embodiment only of my invention, and it will be understood that other embodiments may be made differing therefrom in many particulars as, for example, in the form and mounting of the shutters, the trace rod mechanism, and the operation thereof, without departing from the spirit and scope of the invention as set forth in the following claims.

I claim:

1. Shutter mechanism for an organ comprising a frame, a plurality of shutters mounted therein for movement between a closed position of the mechanism in which the shutters assume a position at approximately 45° to the plane of the frame, the edges of adjacent shutters being in contact, and a fully opened position of the mechanism in which the shutters assume a position at approximately 90° to the plane of the frame, whereby when the shutters are opened passages are provided for the tones to pass without deflection, and means for moving the shutters.

2. Shutter mechanism for an organ comprising a rectangular frame, a plurality of shutters pivotally mounted therein for movement between a closed position of the mechanism in which the shutters assume a position at approximately 45° to the plane of the frame, the edges of adjacent shutters being in contact, and a fully opened position of the mechanism in which the shutters assume a position at approximately 90° to the plane of the frame, whereby when the shutters are opened passages are provided for the tones to pass without deflection, and means for moving the shutters.

3. Shutter mechanism for an organ comprising a rectangular frame, shutters pivotally mounted in said frame at the ends thereof, the shutters being at approximately 45° to the plane of the frame with one edge of each shutter in contact with an edge of an adjacent shutter when the shutter mechanism is closed, shelves carried by the frame, with which shelves edges of the end shutters contact when the mechanism is closed, and means for moving said shutters into a position at approximately 90° to the plane of the frame, whereby pas-

sages are provided for the tones to pass without deflection.

4. Shutter mechanism for an organ comprising a rectangular frame, a plurality of shutters pivotally mounted in said frame at the ends thereof, said shutters when the mechanism is closed assuming a position at approximately 45° to the plane of the frame with one edge of each shutter in contact with an edge of an adjacent shutter, and when the mechanism is opened assuming a position at approximately 90° to the plane of the frame, shelves carried by the frame, with which shelves edges of the end shutters contact when the mechanism is closed, and means for moving the shutters to and from such position.

5. Shutter mechanism for an organ comprising a frame, a plurality of shutters mounted therein for movement between a position in which the mechanism is fully closed and a position in which the mechanism is fully opened, the shutters in the first named position being at an angle of approximately 45° to the frame, having the edge of one shutter in contact with the side of the edge of the other shutter and, in the second named position, being parallel to each other at an angle of approximately 90° to the frame, and means for moving the shutters.

6. Shutter mechanism for an organ comprising a frame, a plurality of shutters mounted therein for movement between a position in which the mechanism is fully closed and a position in which the mechanism is fully opened, the shutters in the first named position being at an angle of approximately 45° to the frame, and in the second named position being at an angle of approximately 90° to the frame, means on one side of said frame for moving alternate shutters in one direction and means on the other side of said frame for moving the remaining shutters in a direction opposite to that in which the alternate shutters are moved by the first mentioned means.

7. Shutter mechanism for an organ comprising a frame, a plurality of shutters mounted therein for movement between a position in which the mechanism is fully closed and a position in which the mechanism is fully opened, the shutters in the first named position being at an angle of approximately 45° to the frame and in the second named position being at an angle of approximately 90° to the frame, means for moving alternate shutters in one direction and means for moving the remaining shutters in a direction opposite to that in which the alternate shutters are moved by the first mentioned means.

8. Shutter mechanism for an organ comprising a frame, a plurality of shutters mounted therein for movement between a position in which the mechanism is fully closed and a position in which the mechanism is fully opened, the shutters in the first named position being at an angle of approximately 45° to the frame and in the second named position being at an angle of approximately 90° to the frame, and means for simultaneously moving alternate shutters in one direction and the remaining shutters in a direction opposite to that in which the alternate shutters are moved.

MAURICE E. HARDY.
